(57) **CLAIM**

We claim the ornamental design for a footwear heel, as shown and described.

DESCRIPTION

FIG. 1 is a rear view of a footwear heel, showing our new design; and,

FIG. 2 is a side view of the footwear heel.

The broken lines shown in FIGS. 1 and 2 show unclaimed subject matter only and form no part of the claimed design.

1 Claim, 1 Drawing Sheet

FIG. 1

FIG. 2
